UNITED STATES PATENT OFFICE.

THOMAS SHIPLEY, OF YORK, PENNSYLVANIA, ASSIGNOR, BY MESNE ASSIGNMENTS, TO YORK ICE MACHINERY CORPORATION, OF YORK, PENNSYLVANIA, A CORPORATION OF DELAWARE.

VERTICAL SHELL AND TUBE CONDENSER.

Application filed July 20, 1926. Serial No. 123,764.

This invention relates to heat exchangers, and particularly to a vertical shell and tube condenser of the water cooled type used in certain refrigerating plants. In such condensers the quantity of cooling water necessarily used may be reduced if the water be caused to flow in thin films down the interior surfaces of relatively large tubes.

The purpose of the present invention is to accomplish this desirable result by a simple and inexpensive means.

The preferred embodiment of the invention is illustrated in the accompanying drawings, in which—

15 Figure 1 is a vertical axial section of the upper part of the condenser shell showing the tube sheet and the upper ends of the tubes and showing my water deflector construction applied.

20 Figure 2 is a plan view of the same, part of the distributing plate being broken away to disclose the arrangement of the deflectors in the tubes.

25 Figure 3 is an enlarged sectional detail of a fragment of the tube sheet and the upper end of one tube showing the water deflector in place. In this view the deflector is shown partly in section.

30 Figure 4 is a view similar to Figure 3, the plane of section through the tube and tube sheet being at right angles to the plane of section of Figure 3.

Figure 5 is a perspective view of the deflector.

35 Referring first particularly to Figures 1 and 2, the condenser shell is shown at 11, the flanged tube sheet or head at 12, and the welded joint connecting the tube sheet and shell at 13. The tubes are shown at 14.

40 Resting in the upper end of each tube is a deflector indicated generally by the reference numeral 15. This deflector is of special construction and consists of a hollow cone 16 suspended with its apex upward. The periphery at the base of the cone forms a relatively sharp drip line and its diameter is such that a small annular space remains between the periphery of the base of the cone and the interior surface of the corresponding tube 14. This cone is suspended and positioned by a pair of suspension lugs 17 which rest on the upper end of the tube, and is positioned in a direction at right angles to the lugs 17 by a pair of position-

ing lugs 18. Loop 19 is formed between the 55 lugs 17 and offers a convenient hand hold for removing the deflector.

Resting on the tube sheet 12 near the periphery thereof is an upstanding cylindrical shell 20 which forms a water box. 60 Extending across the shell 20 at about a third of the distance from the bottom of such shell, is a horizontal perforated diaphragm 21 which serves as a distributor plate. Perforations 22 allow the water 65 admitted to the top of the shell 20 to fall in small streams or drops approximately uniformly throughout the area of the tube sheet 12. A pair of lifting loops 23 are attached to the plate 21 and serve as a 70 means for removing the entire distributor structure from the top of the condenser.

In order to control the flow of water through the perforations 22 at the center of the plate 21, as compared with the flow 75 through these perforations near the periphery of the plate, a pair of register rings 24 and 25 having register slots 26 through them are mounted on and above the plate 21. The water supply pipe 27 discharges 80 into the space within these two register rings. One ring is fixed and the other is adjustable angularly relatively thereto to vary the effective area of the slots 26. In this way it is possible to limit to the extent 85 desired the flow of water to the annular space between the register rings and the shell 20. Plate 21 is sustained at the center by a strut member 28.

90 In operation, water entering through the pipe 27 flows into the space within the register rings 24 and 25. Part flows thence directly through the perforations 22 within the register rings. Another part flows through the slots 26 and thence through the 95 perforations 22, outside the register rings. Thus the rate of flow through the central area and the surrounding annular area may be adjusted relatively to each other. The purpose is to secure approximately uniform 100 flow of water to all parts of the tube sheet.

105 This water overflows the upper ends of the tubes 14 and directed in part by the deflectors 15 continues to flow in contact with the internal surface of these tubes. Not only do the deflectors 15 direct the water against the tube walls but they arrest and deflect any drops of water which might

otherwise fall directly from a perforation 22 in the plate 21 through the bore of a tube beneath it. It follows that the condenser 5 operates effectively with a minimum quantity of cooling water.

Another advantage is that the device is simple and inexpensive to construct and very accessible for cleaning. This matter of 10 cleaning is a very important one because of the disturbing effect of fungus growths which are encountered in this service and which make occasional cleaning necessary. In this connection a very simple form of 15 deflector is of the utmost importance, as it lends itself to easy cleaning and does not lend itself to the accumulation of obstructing growths.

Various changes of detail may be made 20 without departing from the spirit of the invention.

What is claimed is:

1. The combination with a vertical heat 25 interchanger tube of a liquid deflector mounted within the upper end of the tube and comprising a downward and outward flaring conical deflector of slightly smaller diameter than and mounted within the interior of the tube arranged to deflect water into contact with the internal wall of the 30 tube.

2. The combination with a vertical heat 35 interchanger tube of a liquid deflector suspended in the upper end of said tube, said deflector comprising a conical member having a base slightly smaller in diameter than the interior of the tube, and suspending and positioning lugs adapted to engage the upper margin and the interior wall of the tube.

3. The combination with a vertical shell 40 and tube heat interchanger of a perforated plate for distributing water uniformly in small streams over the tube area; and a plurality of liquid deflectors mounted within the upper ends of the various tubes and 45 each comprising a conical deflector of slightly smaller diameter than the interior of the tubes, arranged to deflect the water into contact with the wall of the tube.

4. The combination with a vertical shell

and tube heat interchanger, of a water supply 50 arranged to discharge cooling water over the center of the upper end of the shell; a horizontal perforated diaphragm interposed in the path of such water and adapted to distribute such water in small streams 55 over the tube area; and an annular register-gate for controlling the flow above the diaphragm from the center of the diaphragm to the marginal portions thereof.

5. The combination with a vertical shell 60 and tube heat interchanger, of a water supply arranged to discharge cooling water over the center of the upper end of the shell; a horizontal perforated diaphragm interposed in the path of such water and adapted to 65 distribute such water in small streams over the tube area; an annular register-gate for controlling the flow above the diaphragm from the center of the diaphragm to the marginal portions thereof; and conical deflectors mounted within the upper ends of the tubes and arranged to deflect the falling water into contact with the walls of the 70 tubes.

6. The combination with a vertical heat 75 interchanger tube, of an imperforate liquid-deflector supported within the upper end of the tube, and having a pendant marginal rim spaced from the wall of the tube.

7. The combination with a vertical heat 80 interchanger tube of a downwardly and outwardly flaring liquid-deflector, of substantially conical form, recessed on its lower face to afford a pendant marginal rim spaced from the wall of the tube, said deflector 85 being mounted within said tube.

8. The combination with a vertical heat 90 interchanger tube, of a downwardly and outwardly flaring liquid deflector, of substantially conical form, recessed on its lower face to afford a pendant marginal rim spaced from the wall of the tube, and suspending means for said deflector adapted to rest upon the upper margin of the tube.

In testimony whereof I have signed my 95 name to this specification.

THOMAS SHIPLEY.
